HENRY G. VOIGHT, OF NEW BRITAIN, CONNECTICUT, ASSIGNOR TO SARGENT & COMPANY, OF NEW HAVEN, CONNECTICUT, A CORPORATION OF CONNECTICUT.

LOCK.

1,177,745.

Specification of Letters Patent.

Patented Apr. 4, 1916.

Application filed October 5, 1915. Serial No. 54,206.

To all whom it may concern:

Be it known that I, HENRY G. VOIGHT, of New Britain, county of Hartford, and State of Connecticut, have invented certain new and useful Improvements in Locks, of which the following is a full, clear, and exact description.

This invention relates to locks, and more particularly to tumbler mechanism of locks for the corridor doors of hotels.

One of the objects of the invention is to provide a very secure type of tumbler mechanism which has a very smooth and well balanced action.

Another object of the invention is to provide an improved tumbler spacer of such form that the several spacers not only space the tumblers apart so that they will register properly with the wards in the key, but also bear on the tumblers in such a way as to cause friction, and thereby act as a yielding buffer on the return movement of the tumblers, so that the lock is rendered almost noiseless in operation.

To these and other ends, the invention consists in the novel features and combinations of parts to be hereinafter described and claimed.

In the accompanying drawings, Figure 1 is a side elevation of a mortise lock embodying my improvements, with the lower portion of the case omitted; Fig. 2 is a fragmentary elevation with the cap plate removed, the bolt being in the retracted position; Fig. 3 is a view similar to Fig. 2, showing the bolt partly protracted by the key; Fig. 4 is a section on line 4—4 of Fig. 2; Fig. 5 is a section on line 5—5 of Fig. 2; Fig. 6 is a section on line 6—6 of Fig. 2; Fig. 7 is a reverse view of the parts shown in Fig. 1; Fig. 8 is a fragmentary elevation, showing the bolt protracted, and with the main tumblers removed from in front of the bolt; Fig. 9 shows the bolt with a single tumbler overlying the same, the other tumblers of the same group and the tumbler spacers being omitted; Fig. 10 is a detail of one of the tumbler spacers; Fig. 11 is a detail of one tumbler and the two tumbler spacers on opposite sides thereof; and Fig. 12 is a detail of the key.

The main portion of the lock case 20 is of usual construction being provided with the ordinary face plate or front 21, through

which the dead bolt 22 is adapted to extend. 55 In the particular form shown, this bolt 22 is operable by a key inserted through a key-hole 23 in the cap or cover plate 24. This cap or cover plate 24 is, generally speaking, of the usual type, but its detail construction is somewhat out of the ordinary, because at one corner it is provided with a cut-away portion 25 which fits around a plate 26 that serves to hold the tumbler mechanism of the bolt 22 in the properly 60 assembled condition. The cap 24 is also provided with an opening 27 fitting around a disk 28, which also serves as a means for clamping the tumbler mechanism in position. This particular construction facilitates the assembling of the lock for, after the dead bolt and its tumblers have been assembled in the case, as hereinafter described, they can be permanently maintained in the assembled position by the 65 members 26 and 28, while other bolt mechanism is assembled in another portion of the case (in this instance, the lower part of the case). The cap 24 can then be applied by screws in the usual manner, without the 70 necessity of observing any particular care in applying it, at least so far as the bolt 22 and its tumbler mechanism is concerned.

The bolt 22 has a shank 29 guided to and fro by a lug 30 projecting from the back 85 wall of the case. At its rear portion, it is provided with talons 31 adapted to be engaged by the bit 32 of the key 33, when the latter is inserted into the keyhole 23. In the particular form shown, the talons 31 are 90 formed on the lower part of the bolt shank, and at the upper edge of said shank notches 34, 35 are provided to coöperate with a stump or fence 36 on a racking lever 37, pivoted to the case at 38, and acted on by a 95 spring 39. The spring 39 tends to engage the stump or fence, with the notch (34 or 35) with which it is alined. Fig. 8 shows the fence 36 engaged in the notch 35, and thereby locking the bolt in its protracted 100 position. When the fence engages the notch 34, it locks the bolt in its retracted position. The racking lever 37 is operated positively by means of the key through a lifter 40, which preferably takes the form of an elbow 105 lever, pivoted at 41, and having an arm 42 in close proximity to the keyhole. As the key is turned in the keyhole, the arm 42 is

engaged and moved upward so that a small projection 43 thereon will engage a coöperating projection 44 on the racking lever 37, and thereby raise the stump or fence 36 5 out of the bolt notch in which it is engaged, thereby releasing the bolt for proactive or retractive movement, as the case may be. The lower arm 45 of the lifter 40 is adapted to engage a stop pin 46 10 on the case. In the normal position, the lifter 40 hangs in the position shown in Fig. 8, in which it is arrested by the pin 46. A curved guard 47 cast on the back of the case is disposed between the keyhole and the 15 lower arm 45 of the lifter 40 to prevent tampering with the latter, by means of the wire or the like inserted in the keyhole. The racking lever 37 is in the nature of a bolt-locking tumbler, and therefore it will be 20 correct to refer to the member 45 as a tumbler lifter.

It will be observed that the key releases the bolt by acting on the racking lever or locking tumbler 37, through the intermediary of the tumbler lifter 40, whereupon it shifts the bolt by engagement with the talons 31. The bolt can only be actuated, therefore, by a key bitted to actuate the tumbler lifter 40 in an operative fashion with 30 respect to the racking lever. The security of the lock is, however, considerably increased by providing additional tumbler mechanism, preferably comprising a plurality of pivoted tumblers that coöperate with the racking 35 lever and have to be moved by the key into a certain definite position before the racking lever can be released from locking engagement with the bolt by means of the key. In other words, these additional tumblers serve 40 primarily as locking tumblers for the locking tumbler or racking piece 37, rather than as tumblers for directly locking the bolt. In Fig. 9, I have shown one of these tumbler-locking tumblers at 48. In the particular form shown, this tumbler 48 is pivoted 45 to the case on a post 49, and provided with a spring 50 reacting against the lug 30. At its rear end portion, it is provided with a sweep 51 adapted to be engaged by the key, and at its upper portion it is provided with 50 a cut-away portion 52 entering the same from one edge and adapted to slide over the racking piece or stump 36 in what is generally a forward and rearward direction as 55 said tumbler 48 is actuated by the key. The cut-away portion 52 extends into the tumbler 48 from the forward edge of the latter, and at the upper part of said cut-away portion one or more notches 53 are provided, 60 the construction being such that the racking piece 36 cannot be lifted out of locking engagement with the bolt except when the notch 53 is brought into alinement with said racking piece. This is done by proper biting 65 of the key, as will be apparent. In the

particular form shown, a plurality of additional tumblers 54, 55 and 56 generally similar to the tumbler 48 are mounted on the same pivot 49. These additional tumblers have cut-away portions and notches corresponding to the cut-away portion 52 and notch 53, but on different tumblers the notches are differently located, the key being bitted to shift the several tumblers to different angles in order to bring a series of notches into alinement with the racking piece or stump 36 in order to release the bolt. 70

Interposed between the several tumblers just described are spacers 57, one of which is shown in detail in Fig. 10. This spacer 80 comprises a thin sheet of brass or similar metal adapted to be fixed in position so that the adjacent tumblers at opposite faces slide over the same in being swung to and from the bolt-releasing position. Each spacer 57 85 is provided at the lower portion with a perforation 58 fitting over the tumbler post 49, and at its forward edge it is provided with a notch 59 engaging the lug 30. As the spacer is slipped over the tumbler post, the 90 forward portion of such spacer straddles the lug 30, so that the spacer is thereby rigidly supported. At the tail portion, which is located near the sweep portions of the adjacent tumblers, the spacer is provided with 95 a kerf 60, dividing said tail into two parts which are bent laterally in opposite directions, as shown more particularly in Fig. 11. One of these bent tail parts is indicated at 100 61, and the other at 62, and it will be observed that at the crotch of the kerf a small perforation 63 is provided which serves to hold a certain amount of oil or other lubricant, so that the tumbler movement can be made as easy and noiseless as possible. Fig. 105 11 illustrates one of the tumblers, for example the tumbler 55, with spacers 57 at opposite sides thereof, the tumbler being in the raised position. The tongue 61 of one spacer, and the tongue 62 of the other spacer, 110 project toward each other, beneath the lower edge of the tumbler, and owing to the spring of the metal they serve to yieldingly check the tumbler as the latter moves back to its initial position after being released by the 115 key. The spacers, therefore, act in the nature of yielding buffers which cushion the tumblers and cause them to be returned noiselessly. This is a feature of considerable advantage, because many hotel locks are 120 seriously objectionable on account of the considerable noise incident to the shooting and withdrawal of the bolts. A shut-out device 64 is pivoted on the post 49 over the uppermost or outermost spacer 57, and is 125 adapted to coöperate with a stump 65 on the bolt, but inasmuch as it forms no part of the present invention it will not be described in further detail.

The disk 28 previously described is placed 130

- in position on top of the post 49 when the tumbler mechanism has been completely assembled, and is secured on said post in tumbler clamping position, by means such as a 5 screw 66. The tumbler-holding plate 26, previously described, extends across the rear portions of the tumblers, and is held in place by means such as screws 67, 68, which enter suitable sockets cast on the case wall. 10 It will be understood that the plate 26 is supported in part on the upstanding wall or rim of the case, and in part on the tumbler mechanism. By providing a tumbler-holding part or parts which are disposed within 15 cut-away portions of the cap, the space in the lock case is economized to the fullest extent, because it is unnecessary to interpose a separate tumbler-holding member between the cap plate and the tumbler mechanism. 20 In other words, the use of a tumbler holder which is accommodated in a cut-away portion of the cap does not necessitate any increase in the depth of the case, as will be obvious. 25 Various changes may be made in the detail of the construction without departing from the scope of the invention as defined in the claims.
- What I claim is:—
- 30 1. In a lock, the combination of a dead-bolt, a locking tumbler therefor, a tumbler for locking said locking tumbler in position, a key having a bit to engage said last-named tumbler and actuate the same to release said first tumbler, and means interposed between the key bit and said first tumbler for positively moving said tumbler out of locking engagement with the bolt by means of said key; substantially as described.
  - 35 2. In a lock, the combination of a dead-bolt, a locking tumbler therefor, a plurality of tumblers for locking said locking tumbler in position, a key having a bit to engage said last-named tumblers and operate the same, and means other than the bolt for moving said first-named tumbler out of locking engagement with the bolt when said tumbler has been released; substantially as described.
  - 40 3. In a lock, the combination of a dead bolt, a pivoted racking piece or locking tumbler for locking the bolt in protracted or retracted position, a tumbler for locking said racking piece in bolt-locking position, a key for actuating said second tumbler directly, and a tumbler lifter actuated by the key to shift the first tumbler when it has been released by the second tumbler; substantially as described.
  - 45 4. In a lock, the combination of a dead bolt having a notch, a tumbler having a stump or fence to engage said notch, a tumbler for locking said first tumbler in position having a part to block or release said stump or fence, and a key to actuate said tumblers and shift the bolt; substantially as described.
  - 50 5. In a mortise lock, the combination of a case, bolt mechanism therein, a plate superposed on said bolt mechanism for clamping the same in position, a screw for securing said clamping plate to the case, and a cap plate for the case having a cut out portion fitting around said clamping plate in the plane of the latter; substantially as described.
  - 55 6. In a lock, the combination of a dead bolt having a notch, a pivoted racking piece having a stump or fence to engage said notch, a lifter for actuating said racking piece, a key for operating said lifter, and a locking tumbler for said racking piece adapted for actuation by said key and co-operating with said stump or fence; substantially as described.
  - 60 7. In a lock, the combination of a dead-bolt having a notch, a pivoted racking piece having a stump or fence to engage said notch, a pivoted locking tumbler for said racking piece having a cut-away portion at its forward edge in which said stump or fence operates, and a notch extending upwardly from said cut-away portion, said racking piece locked against movement to release the bolt except when said stump or fence is in registry with the notch in said locking tumbler; substantially as described.
  - 65 8. In a lock, the combination of a dead-bolt, a tumbler for said bolt, and a fixed member alongside said tumbler having a laterally projecting part passing underneath the tumbler for cushioning the return movement thereof; substantially as described.
  - 70 9. In a lock, the combination of a dead-bolt, two tumblers for said bolt, and a relatively fixed spacing plate interposed between said tumblers and having a laterally projecting portion constructed to act as a yielding buffer for both tumblers; substantially as described.
  - 75 10. In a lock, the combination of a dead-bolt, two tumblers for said bolt, and a member interposed between said tumblers and having laterally projecting resilient parts located beneath both of said tumblers to cushion the return movement thereof; substantially as described.
  - 80 11. In a lock, the combination of a dead bolt, a plurality of pivoted tumblers associated therewith, a pivot for said tumblers, a plurality of spacers engaging the tumbler pivot, said spacers provided with notches, and a lug on the case engaged by said notches so as to prevent turning movement of the spacers; substantially as described.
  - 85 12. A tumbler spacer having a resilient laterally projecting buffer portion; substantially as described.

13. A tumbler spacer comprising a thin metal plate having a buffer portion at one extremity thereof; substantially as described.
14. A tumbler spacer having divergent buffer portions adapted to engage tumblers on opposite sides respectively of the spacer; substantially as described.
15. A tumbler spacer having a kerf, the portions on opposite sides of the kerf being bent laterally in opposite directions; substantially as described.

16. In a mortise lock, the combination of a case, a bolt therein, tumbler mechanism for said bolt, a clamping member for holding said tumbler mechanism in assembled position, superposed on said tumbler mechanism, and a cover or cap plate having a cut-away portion to receive said clamping member in the plane thereof; substantially as described.

In witness whereof, I have hereunto set my hand on the 1st day of October, 1915.

HENRY G. VOIGHT.
